(57) **CLAIM**

We claim the ornamental design for an elastic shoulder support with shoulder pad and pivot, as shown and described.

DESCRIPTION

FIG. 1 is a front perspective view from above of an embodiment of the claimed design;

FIG. 2 is a bottom perspective view of the claimed design of FIG. 1;

FIG. 3 is a front view of the claimed design of FIG. 1;

FIG. 4 is a back view of the claimed design of FIG. 1;

FIG. 5 is a right side view of the claimed design of FIG. 1;

FIG. 6 is a left side view of the claimed design of FIG. 1;

FIG. 7 is a top view of the claimed design of FIG. 1; and,

FIG. 8 is a bottom view of the claimed design of FIG. 1.
